SHUNT FOR ELECTRIC BLASTING CAPS

Waldo C. Wilson, Wilmington, Del., assignor to
E. I. du Pont de Nemours & Company, Wil-
mington, Del., a corporation of Delaware

Application November 1, 1932, Serial No. 640,608

11 Claims. (Cl. 102—10)

This invention relates to an improved electric blasting cap assembly, and more particularly to a means for short-circuiting the leading wires of blasting caps to protect the caps from firing by accidental contact of the wires with stray currents or other electric charges during transportation or handling preliminary to actual firing of the detonators to which the leading wires are connected.

Blasting caps consist generally of cylindrical containers, of metal or other suitable material, containing one or more explosive charges capable of sudden and violent explosion under the action of suitable initiating means. In the case of electric blasting caps, the ignition of the explosive is brought about electrically by passing an electric charge through or into the cap. For this purpose two leading wires pass into the cap shell, insulated one from the other and from the shell wall, and the wires are connected by a bridge wire of small diameter. This bridge wire passes through the ignition charge in the cap and, when brought to incandescence by the passage of the electric current, causes the firing of the cap.

The leading wires of electric blasting caps are of considerable length, varying generally from 4 to 20 feet, and are covered with insulating material throughout their length, except several inches of the free end portions of the wires which are left bare in order to facilitate making the proper connections with a source of electric current after the caps are placed in position for firing. The presence of these uninsulated end portions of the wires has always presented a considerable hazard during transportation and handling of the blasting caps both out of and in the mines, because of the possibilities of these exposed ends coming in contact with electric circuits or stray currents in the vicinity of blasting operations. This is particularly true in mining operations where the workmen frequently carry the blasting caps to the place of use with the ends of the wires dragging on the ground and accidentally contacting with objects charged with electricity.

Various methods and means have heretofore been suggested for overcoming these disadvantages and safeguarding against the accidental discharge of electric blasting caps prior to placing the caps in the main explosive charges for properly controlled detonation. One method and means has comprised short-circuiting the leading wires by twisting the bare ends together for a short distance at the termination of the insulation, including preferably a portion of the uninsulated as well as a portion of the insulated wires, so that, in case of contact of the bare ends with

an electric circuit or an electrically charged object, a shunting action will result and insufficient current will pass through the blasting cap to cause firing. While this means and method has given considerable satisfaction, it has the disadvantage that the wires when once twisted and then untwisted are slightly distorted so as to make them more difficult to connect as efficiently with the firing circuit.

Other attempts to accomplish this same result have been made, principally by means of clips of one form or another which are placed on the bare wires to hold them in contact with one another, but these have in general been unsatisfactory because of the difficulty of removing them from the wires after the blasting caps are in place for firing blasting charges, and have the further disadvantage that the clips are sometimes spaced sufficiently far from the termination of the insulation that stray currents may contact the bare wires between the ends of the insulation and the clips or at the junction of the bare wires and thus defeat the primary purpose of the clip.

An object of this invention is to provide a more efficient and satisfactory means for safeguarding the handling and transportation of electric blasting caps. A further object of my invention is to provide a short-circulating device that not only properly contacts the bare wires of blasting caps but at the same time is capable of protecting that portion of the wires between the point of contact and the ends of the insulation. A still further object is such a means which causes no bending or distortion of the bare ends of the wires and at the same time can be easily removed. Other and further objects will present themselves as the description of the invention proceeds, wherein:

Figures 2, 4, 6, 8, 10 and 12 are perspective views of the various modifications of my invention. Figures 1, 3, 5, 7, 9 and 11 are plan views of the blanks from which the clips are formed by bending. Fig. 13 is a perspective assembly view of one form of my invention applied to the lead wires of an electric blasting cap.

These objects are accomplished by the following invention in which I have found that a suitable shunting means for this purpose may be constructed from a resilient piece of conductive metal comprising a main section having diametrically opposed projections positioned to press firmly against each other to engage the bare ends of the wires that are inserted through an opening in the main section. This is so constructed that the bare ends of the wires are adapted to protrude sufficiently through the engaging projections that

the gap between the points of contact with the bare wires and the termination of the insulation will lie substantially within the device and be protected from electric currents with which the wires 5 may otherwise come in contact. These wires are held firmly in position by reason of the spring or resilient effect of the metal, the uninsulated portions of the wires being held in direct contact with one another, or in firm contact with the metal of 10 the shunting device in order to short-circuit the electric blasting cap with certainty in case the bare ends of the cap wires come into contact with any electric charge so long as the shunting device remains attached to the wires. This device may 15 also be used for twisting the wires together at a point about the termination of the insulated portions to effect a greater security against premature detonation of the blasting caps to which the wires are attached. This may be accomplished by holding the wires in one hand while rotating the device with the other hand, or vice 20 versa, using the wires as an axis.

While I have described the broad fundamental 25 principles of my invention in the foregoing, it may be embodied in various specific modifications, some of which are described below with reference to the accompanying drawing.

Figure 1 shows a strip of metal suitable for 30 working or shaping into final form to comprise one of the embodiments of my invention. Figure 2 represents a view in elevation of the completed device ready for attachment to the leading wires. In these figures D represents an opening through that portion of the metal plate A forming the 35 base. Sections B—B' form the outer sides of the resilient projections. While these side portions may meet as substantially straight surfaces at their ends I preferably bend them inwardly upon themselves in the form of a loop in order to provide vise-like jaws to grip the bare wires inserted therein. These end portions may, of course, be bent outwardly to form similar loops, but I prefer the form illustrated in the drawing, so as to facilitate the insertion of the shunt upon 40 the wires. In utilizing the invention in actual practice, the uninsulated ends of the leading wires are thrust through the hole D and thence between the contacting resilient elements C—C' sufficiently far that the termination of the 45 insulated portion is within the shunt between the opening D and the point of contact of the resilient elements so that that portion of the wires between the points of contact and the insulation may not come into contact with stray currents or 50 other charges of electricity.

In place of bending the end portions of the resilient elements inwardly to form a loop as shown in Figure 2, these ends may, of course, be bent inwardly only sufficiently far to permit the inner 60 faces to contact as flat surfaces against each other. These surfaces may also be roughened or slightly corrugated so as to prevent sidewise movement of the wires.

Another modification of my invention is shown 65 in Figures 3 and 4 in which two metallic side pieces or shields E—E' are included which are bent into a plane perpendicular to the base A.

The principal advantage of this modification is 70 that these side portions E—E' prevent sidewise movement of the ends of the bare wires and prevent them from slipping out of the contacting resilient elements of the shunt as well as further preventing that portion of the bare wires between the opening D and the jaws of the vise from com-

ing into contact with pointed or other electrically charged objects.

A further modification of this invention is illustrated in Figures 5 and 6, Figure 5 illustrating a T section of metal, while Figure 6 illustrates the finished shunt. It will be noted that Figure 4 is similar to Figure 1 except for the additional portions F and G. In this modification the portions F—G are bent into a plane perpendicular to A and then G is bent over in a plane parallel to the 10 base A before the sections B—B' are bent upwardly to form the vise-like jaws by means of the loop portions C—C'. With the section G horizontally positioned above the base A, the opening D' will register with the opening D in the base. 15 This provides a guard which aids in maintaining the wires in direct alignment and assists the jaws, in combination with the base A, in securely protecting the wires, as well as preventing sidewise movement. The wires are shunted in the 20 same manner as described in Figure 1 by inserting the bare wires first through openings D—D' and thence through the jaws of the vise so that a substantial length of the bare portions protrude.

A still further modification of this invention is 25 illustrated in Figures 7 and 8, which resemble Figures 1 and 2, except that the portions C—C' are omitted. In this modification the sections B—B' are slightly longer and are bent upwardly and inwardly to form a triangle with the base section A. The outer edges of the sections B—B' may be left smooth or may be provided with jagged or tooth-like contacting surfaces H—H' so that the wires may be securely held in place against 30 sidewise movement.

Figures 9 and 10 illustrate another modification of my shunting means similar to that shown in Figures 1 and 2 but with guards on the resilient end sections C—C' which are bent over into the position shown to aid in preventing the 40 bare wires from working out of or being pushed out of the gripping elements of the shunt during handling of the blasting cap equipped with this shunting means.

Figures 11 and 12 show a modification similar 45 to Figures 7 and 8 but having the contacting edges B—B' in the form of corrugated surfaces so as to firmly hold the bare wires from sidewise movement when the shunt is in place.

Figure 13 illustrates an assembly of an electric 50 blasting cap and this novel shunting device. The detonating cap is designated M having two leading wires N—N' with the wires stripped of the insulation near their ends as shown at O—O'. In this figure the bare ends have been thrust through the opening D of the base A and, to a substantial extent of their length, through the gripping elements C—C' so that the termination of the insulation is within the shunt, while the bare wires are short-circuited against premature detonation of the cap. The modifications illustrated in the other figures of the drawing are similarly attached.

It will be apparent from the foregoing that various embodiments of my invention exist and may 65 be practiced within the scope thereof and I, therefore, do not intend to be limited in my invention except as indicated in the following patent claims.

I claim:

1. In an electric blasting cap, a shunting device 70 of resilient conductive material for short-circuiting the leading wires comprising a main or base section, diametrically opposed contact members secured thereto and forming a vise at their point of juncture, an opening in the main section 75

- through which the leading wires are adapted to protrude with the bare ends secured in the vise, and a guard for the wires.
2. In an electric blasting cap a shunting device of resilient conductive material for short-circuiting the leading wires comprising a main or base section, diametrically opposed contact members secured thereto and forming a vise at their point of juncture, an opening in the main section through which the leading wires are adapted to protrude with the bare ends secured in the vise, and a guard intermediate the base member and the contact members to prevent lateral movement of the wires.
3. In an electric blasting cap a shunting device of resilient conductive material for short-circuiting the leading wires comprising a main or base section, diametrically opposed contact members secured thereto and forming a vise at their point of juncture, an opening in the main section through which the leading wires are adapted to protrude with the bare ends secured in the vise, and a guard in spaced relation with the base member.
4. In an electric blasting cap, a shunting device of resilient conductive material for short-circuiting the leading wires comprising a main or base section, diametrically opposed contact members secured thereto and forming a vise at their point of juncture, an opening in the main section through which the leading wires are adapted to protrude with the bare ends secured in the vise, and a pair of guards substantially vertical to the base or main section.
5. In an electric blasting cap, a shunting device of resilient conductive material for short-circuiting the leading wires comprising a main or base section, diametrically opposed contact members secured thereto bent into triangular position and forming a vise at their point of juncture, an opening in the main section through which the leading wires are adapted to protrude with the bare ends secured in the vise, and a pair of guards extending across the open sides of the triangle.
6. The device of claim 2 in which the guard is spaced from the base or main section but is substantially in parallel relation therewith, and an opening in the guard registering with the opening in the main section.
7. In an electric blasting cap, a shunting device of resilient conductive material for short-circuiting the leading wires comprising a main or base section, diametrically opposed contact members secured thereto and forming a vise having a jagged or irregular surface at their point of juncture, and an opening in the main section through which the leading wires are adapted to protrude with the bare ends secured in the vise.
8. In an electric blasting cap, a shunting device of resilient conductive material for short-circuiting the leading wires comprising a main or base section, diametrically opposed contact members secured thereto and forming a vise with a roughened surface at their point of juncture, and an opening in the main section through which the leading wires are adapted to protrude with the bare ends secured in the vise.
9. The combination with a detonator, the individual bifilar lead wires of which have a covering of insulated material thereon for a portion of their length outwardly and being bare therebeyond, of a shunt of resilient conductive material for short-circuiting the leading wires comprising a portable main or base section, diametrically opposed resilient elements secured thereto and having a tendency to firmly contact at their outer ends, and an opening in the main section through which the leading wires protrude with the bare ends secured between the resilient elements, so that the point where the insulation terminates and the bare portion begins lies between the main or base section and the resilient contact elements.
10. The combination with an electric detonator and its lead wires, said lead wires being bare for a portion of their length at the outer ends and being insulated for the remainder of their length inwardly to the detonator, of a shunt consisting of resilient conductive material for short-circuiting the leading wires comprising a portable main or base section, a pair of diametrically opposed resilient elements secured thereto and in spaced relation to each other at the junction with the base member and having a tendency to resiliently and firmly contact with each other at the outer ends, and an opening in the main section through which the leading wires protrude with the bare ends secured between the resilient elements, so that the point where the insulation terminates and the bare portion begins, lies between the main or base section and the resilient contact elements.
11. The combination with an electric detonator and its lead wires, said wires having a substantial portion thereof covered by insulating material and the portions near their outer ends left bare, of a portable shunt of resilient conductive material for short-circuiting the leading wires comprising a main or base section having an opening therein through which the leading wires are inserted, and diametrically opposed resilient elements secured to the base section and engaging the bare portion of the wires, so that the point where the insulation terminates and the bare portion begins, lies between the main or base section and the resilient contact elements.
